(57) **CLAIM**

The ornamental design for a facial tool, as shown and described.

DESCRIPTION

FIG. 1 Is a front left perspective view of a facial tool, showing my new design;

FIG. 2 Is a back view thereof;

FIG. 3 Is a front view thereof;

FIG. 4 Is a left side view thereof;

FIG. 5 Is a right side view thereof;

FIG. 6 Is a bottom plan view thereof; and,

FIG. 7 Is a top plan view thereof.

The broken lines shown in the drawings represent unclaimed portions of the facial tool and form no part thereof.
